CLEATED PLYWOOD BOX

John W. Ladd, 800 Fair Oaks Ave., Oak Park, Ill.

Filed Apr. 23, 1956, Ser. No. 579,824

8 Claims. (Cl. 217—12)

This invention relates to cleated boxes for packaging and shipment purposes, and more particularly to improved cleated boxes which can withstand greater end thrust loads than the boxes described in my U.S. Patent No. 2,709,020, patented May 24, 1955.

The principal object of this invention is to provide a cleated box having great resistance to heavy end thrust loads, which will take prolonged rough handling and keep major shock forces away from its contents, which is strong but yet light in weight, which presents a smooth interior, which has minimum overall dimensions with maximum internal unbroken storage space, which may be shipped and stored in knockdown condition or partially assembled nested condition thereby saving storage and shipping space, which is simple to assemble without the use of nails or the like, which may be readily filled and packed in partially assembled condition, which may be quickly opened for inspection purposes and the like, and readily reclosed without impairment of box strength, which utilizes a minimum of lumber footage, which eliminates the necessity for metal hardware such as hinges or hasps, and which is inexpensive to manufacture and assemble.

Briefly, the cleated box of this invention includes a first pair of opposed side members each including a panel, and a cleat secured at each end edge of the panel on the inside thereof. It also includes a second pair of opposed side members each including a panel and cleats secured along all of the edges on the inside thereof. It further includes a pair of opposed end members each including a panel. The panels may be made of plywood, ply veneer, reinforced corrugated material, lumber or the like. These members are preferably all prefabricated and the various cleats may be permanently secured to the panels as by clinch nailing or stapling. This assures strong box members capable of rough handling and which may be readily and inexpensively manufactured on a production basis. These prefabricated members may be stored and shipped in knockdown condition which affords considerable saving in handling cost.

In assembling the cleated box of this invention, one of the second pair of opposed side members is laid horizontally and the first pair of opposed side members may be positioned upright by a jig with their panels inside of the cleats of the former side member. However, if desired at this stage, the first pair of opposed side members may be held upright by four unclinched nails to the other side member to lend stability to this sub-assembly during the filling and packing period. In fact, this sub-assembly may be preformed and stored and shipped in a nested condition. The end panels are then slipped in place inside of the end cleats of the pairs of opposed side members. The side edges of the end panels are covered by the panels of the opposed side members. After the box is filled or packed, then the other side member of the second pair of opposed side members is put in place completely to enclose the contents of the box. Then, wire straps may be wrapped around the

2

box sides to hold the box together. In the completely assembled condition of the box, the panels of the opposed side members, in a preferred form of the invention, extend substantially the entire length of the box. The 5 cleats of the second pair of opposed side members extend along the periphery of the sides of the box. The inside cleats of the first pair of opposed side members extend between the end cleats of the other pair of opposed side members. The end panels of the box may be secured in place by driving nails through the end of the box and into the end panels but the contents of the box can suffice to hold the end panels up. The box is secured in assembled condition by securing together the two pairs of side members and this may be readily accomplished by encircling the side members with straps or the like.

The necessity of nailing in assembly is completely eliminated when a jig is used to support the box sides upright during packing and the resulting box is considerably stronger and will take more prolonged rough handling than a conventional nailed box. The various cleats and plywood panels all functionally cooperate with each other toward this end. The box has stability of internal and external shape and distortional stresses are 20 shared by adjacent panel members and supporting cleats. There is balanced resistance to splitting. The construction described is particularly useful where heavy end thrust loads are present. Further, there are no open cracks at any of the joints between the various members.

25 Further features of this invention reside in the details of construction of the cleated plywood box of this invention and in the cooperative relationships between the component parts thereof.

30 Other objects and advantages will become apparent to 35 those skilled in the art upon reference to the accompanying specification, claims and drawings in which:

Fig. 1 is a perspective view of one form of the cleated plywood box of this invention;

Fig. 2 is an exploded perspective view illustrating the 40 side and end members utilized in forming the box of Fig. 1;

Fig. 3 is a vertical sectional view taken substantially along the line 3—3 of Fig. 1;

Fig. 4 is a vertical sectional view taken substantially 45 along the line 4—4 of Fig. 1;

Fig. 5 is a horizontal sectional view taken substantially along the line 5—5 of Fig. 1;

Fig. 6 is a perspective view illustrating another form 50 of the cleated plywood box of this invention; and

Fig. 7 is a fragmentary exploded view of a corner of the box shown in Fig. 6.

Referring first to Figs. 1 to 5 of the drawings, there is 55 illustrated one form of the cleated box of this invention, this box being generally designated at 10. It includes a first pair of opposed side members 11 and 12, a second pair of opposed side members 21 and 22 and a pair of opposed end members 30 and 31. These members are all prefabricated and assembled together for packaging and shipping purposes.

60 The side member 11 of the first pair of opposed side members includes a panel 13 and a cleat 14 secured to and flush with each end edge of the panel 13 on the inside thereof. The four corners of the panel 13 are notched, and the cleats 14—14 terminate at the notches.

65 Just inside the notches cleats 15—15' are located on the outside of the panel 13. The cleats 15—15' terminate flush with the side edges of the panel 13. The inside faces of the cleats 15—15' may be optionally notched at 15"—15". These notches form entry ways 70 for entrance of air between boxes of the type now being described when stacked one above the other. Also, where the boxes are to stand outside, the notches enable

draining of rainwater off the tops of the boxes. An intermediate cleat 15 is secured on the outside of the panel 13 approximately midway between the end cleats 15'-15'. The ends of the intermediate cleat 15 optionally terminate short of the side edges of the panel 13 to form ventilating or rainwater draining passages between the longitudinally spaced sections thereof.

In a like manner, the other opposed side member 12 includes a panel 16 which is notched at the four corners thereof, and a cleat 17 is secured flush with each end edge of the panel 16 on the inside thereof, the cleat terminating at the notches. A pair of cleats 18'-18' are secured to the outside of the panel 16 just inside of the notches of the panel 16 and these end cleats terminate flush with the side edges of the panel 16. These end cleats are optionally notched at the bottom thereof, and an intermediate cleat 18 is provided which terminates short of the side edges of the panel 16. The various cleats associated with the panels 13 and 16 are permanently secured to their associated panels as by clinch nailing, stapling, etc. at 19. In this way, the cleats are permanently and securely fastened to the panels prior to the assembly thereof.

The side member 21 of the second pair of opposed side members includes a panel 23 having cleats 24-24 secured flush with and along the side edges on the inside thereof. These side cleats terminate short of the end edges of the panel 23, and cleats 24'-24' are secured in slightly overlapping relation along the end edges of the panel 23 on the inside thereof, and the ends thereof terminate flush with the side edges of the panel 23. The ends of the side cleats 24-24 are spaced from the end cleats 24'-24' by an amount approximately equal to the widths of the outside end cleats 15'-18' of the first pair of opposed side members. In a like manner, the other side member 22 includes a panel 25 having side cleats 26-26 secured along and flush with the side edges thereof and the inside thereof. These cleats terminate short of the end edges of the panel 25, and cleats 26'-26' are secured in slightly overlapping relation with the end edges of the panel 25, and the ends thereof terminate flush with the side edges of the panel. Also, the ends of the side cleats 26-26 are spaced from the end cleats 26'-26' by an amount approximately equal to the widths of the outside end cleats 15'-18' of the first pair of opposed side members.

The end members 30-31 each comprise a panel sized to engage the panels of the first and second pairs of opposed side members when a box is in its assembled condition. All of the above mentioned panels are preferably made of plywood although other materials suitable for panels, such as ply veneer, reinforced corrugated material, and lumber or the like may be used.

In assembling the cleated box of this invention, the first pair of opposed side members 11 and 12 are placed in position on the side member 21 of the second pair of opposed side members. The side cleats 24-24 are located on the outside of the first pair of opposed side members 11 and 12, and then the bottom side edge of the panel 13 rests on and is covered by the panel 23. The end cleats 24'-24' extend into the corner notches of the panels 13 and 16 of the first pair of opposed side members, the notches thereby providing clearance for the extension of the panels 13 and 16 over the end cleats 24'-24' of the panel 23. The end cleats 15'-15' and 18'-18' on the outside of the panels 13 and 16 extend into the slots defined between the side and end cleats of the panel 23. The bottom ends of the inside cleats 14-14 and 17-17 of the two vertical panels 13 and 16 abut the then upper surfaces of the end cleats 24'-24' of the then horizontal panel 23. If desired, at this stage, the first pair of opposed side members 11 and 12 may be nailed to the other side member 21 and this may be accomplished by driving nails 40 through

the end cleats 24'-24' and 26'-26' into the end cleats 15'-15' and 18'-18'. This lends stability to this sub-assembly for the purposes of filling and packing the same. In fact, this sub-assembly may be preformed and stored and shipped in nested condition thereby saving considerable space in so doing.

The pair of opposed end members 30 and 31 are then slipped into place inside of the end cleat members 14-14 and 24'-24'. The edges of the end members or panels 30 and 31 then engage the inner surfaces of the panels 23, 13 and 16.

After the box is filled or packed then the other side member 22 of the second pair of opposed side members is put in place completely to enclose the contents of the box. Here, the then tops of the outer end cleats 15'-15' and 18'-18' fit into the slots defined between the side and end cleats 26-26 and 26'-26' respectively of the panel 25. The box is secured in assembled relation by securing together the two pairs of side members 11, 12, 21 and 22 in any suitable manner. For example, this may be readily accomplished by encircling the side members with conventional straps 41 or the like. To secure the straps 41 tightly in place, the overlapping ends of the straps may be crimped, as, for example, at 42 and

encased in a sleeve 43. Preferably, the straps overlie the outside cleats 15'-15' and 18'-18'. The assembled strapped box is extremely strong and will take prolonged rough handling and keep major shock away from its contents.

By reason of the construction of the cleated box of this invention there is no necessity for nailing during assembly and the resulting box is considerably stronger than a conventional nailed box. The various cleats and panels all functionally cooperate with each other toward this end. The box is extremely stable and maintains its internal and external shape. There is balanced resistance to diagonal distortion and to edge compression and also great resistance to splitting, and there are no open cracks at any of the joints between the various members. Moreover, the box is particularly suitable with heavy end thrust loads.

When the boxes are stacked one upon the other with the boxes orientated so that one of the first pair of opposed side members as 12 is faced down, ventilating spaces 45 are provided between the boxes into which air may pass through the slots 15"-15" formed by the outside end cleats. Also, there is clearance left between the intermediate outside cleat 15 or 18 and the adjacent side cleats 24-24 or 26-26 so that air may circulate the length 50 of the boxes. These spaces also provide for draining off of rainwater from the box tops.

The form of the invention illustrated in Fig. 6 is essentially the same as that of Figs. 1 to 5 and like reference characters have been utilized for like parts. In the cleated box of Fig. 6, the side cleats 24-24 and 26-26 of the second pair of opposed side members 21 and 22 extend into abutment with the end cleats 24'-24' and 26'-26' thereof. The aforementioned slots between these cleats are therefore omitted. Accordingly, the lengths of the outside end cleats 15'-15' and 18'-18' are reduced so that the ends of these cleats abut the inner surfaces of the side cleats 24-24 and 26-26. The side members of the partially assembled box may be secured together by driving the nails 40 through the side cleats 15'-15' and 18'-18'. In other respects the embodiment of Fig. 6 is substantially identical to that of Figs. 1 to 5.

While for purposes of illustration several forms of this invention have been disclosed, other forms thereof may become apparent to those skilled in the art upon reference 70 to this disclosure; therefore, this invention is to be limited only by the scope of the appended claims.

I claim as my invention:

1. A cleated box comprising, a first pair of opposed side members each including a panel, an end cleat secured

along each end edge of the panel on the inside thereof and terminating short of the outermost side extremities of the associated panel and an end cleat secured to the outside of said panel adjacent to but spaced from each end edge of the panel, said panel being cut away at the four corners thereof up to the ends of said first named cleat thereof, a second pair of opposed side members each including a panel and cleats secured along all of the edges thereof on the inside thereof, and a pair of opposed end members each including a panel, the cleats along the side edges of the second pair of opposed side members being located outside of the first pair of opposed side members, the ends of the outside end cleats of said first pair of opposed side members extending between the side cleats of said second pair of opposed side members, the side edges of the panels of said first pair of side members contacting the panels of said second pair of side members, the panels of said first and second pair of opposed side members extending substantially the length of the box, the end cleats of the second pair of opposed side members passing through said cutaway portions of said panel corners of the first pair of opposed side members, the end faces of said inside end cleats of said first pair of opposed side members contacting the end cleats of said second pair of opposed side members, and said opposed end members being on the inside of said cleats on the ends of the box and all of the edges thereof abutting the panels of said two pairs of opposed side members.

2. A cleated box comprising, a first pair of opposed side members each including a substantially rectangular panel, an end cleat secured along each end edge of the panel on the inside thereof and an end cleat secured to the outside of said panel adjacent to but spaced from each end edge of the panel, a second pair of opposed side members each including a substantially rectangular panel and cleats secured along all of the edges thereof on the inside thereof, and a pair of opposed end members each including a panel, the cleats along the side edges of the second pair of opposed side members being located outside of the panels of the first pair of opposed side members, the ends of the outside end cleats of said first pair of opposed side members bridging the side cleats of said second pair of opposed side members, each of the outside end cleats of said first pair of opposed side members bridging an opposite pair of said cleats of said second pair of opposed side members, the panels of said first and second pair of opposed side members extending substantially the length of the box, said inside end cleats of said first pair of opposed side members bridging the side faces of the end cleats of said second pair of opposed side members, and said opposed end members being on the inside of said cleats on the ends of the box.

3. A cleated box comprising, a first pair of opposed side members each including a substantially rectangular panel, an end cleat secured along each end edge of the panel on the inside thereof and an end cleat secured to the outside of said panel adjacent to but spaced from each end edge of the panel, said latter end cleats being slotted to permit circulation of air when similar boxes are stacked with the first pair of opposed side members being horizontal, a second pair of opposed side members each including a substantially rectangular panel and cleats secured along all of the edges thereof on the inside thereof, and a pair of opposed end members each including a panel, the cleats along the side edges of the second pair of opposed side members being located outside of the panels of the first pair of opposed side members, the ends of the outside end cleats of said first pair of opposed side members bridging the side cleats of said second pair of opposed side members, each of the outside end cleats of said first pair of opposed side members bridging an opposite pair of said cleats of said second pair of opposed side members, said inside end cleats of said first pair of opposed side members bridging the side faces of the end cleats of said second pair of opposed side members, and said opposed end members being on the inside of said cleats on the ends of the box.

said opposed and members being on the inside of said cleats on the ends of the box and all of the edges thereof abutting the panels of said two pair of opposed side members.

5. A cleated box comprising, a first pair of opposed side members each including a substantially rectangular panel, an end cleat secured along each end edge of the panel on the inside thereof, an intermediate cleat secured to the outside of said panel between the ends thereof with at least one end of the cleat spaced a substantial distance from at least one side edge thereof, and an end cleat secured to the outside of said panel adjacent to but spaced from each end edge of the panel, said latter end cleat being slotted to permit circulation of air when similar boxes are stacked with the first pair of opposed side members being horizontal, a second pair of opposed side members each including a substantially rectangular panel and cleats secured along all of the edges thereof on the inside thereof, and a pair of opposed end members each including a panel, the cleats along the side edges of the second pair of opposed side members being located outside of the panels of the first pair of opposed side members, each of the outside end cleats of said first pair of opposed side members bridging an opposite pair of cleats of said second pair of opposed side members, said inside end cleats of said first pair of opposed side members bridging the side faces of the end cleats of said second pair of opposed side members, the ends of the outside end cleats of said first pair of opposed side members bridging the side cleats of said second pair of opposed side members, said intermediate cleat having at least one edge spaced from the adjacent side cleat of the adjacent opposed side member to leave clearance for passage of air, and said opposed end members being on the inside of said cleats on the ends of the box.

5. A cleated box comprising, a first pair of opposed side members each including a panel, an end cleat secured along each end edge of the panel on the inside thereof and an end cleat secured to said panel contiguous to but spaced from each end edge of the panel on the outside thereof and extending up to the sides of the panel, a second pair of opposed side members each including a panel with a cleat along each side edge on the inside thereof whose opposite ends terminate short of the ends of the associated panel and a cleat along each end edge on the inside thereof which is spaced from the ends of the side cleats thereof providing respective slots, and a pair of opposed end members each including a panel, the cleats along the side edges of the second pair of opposed side members being located outside of the first pair of opposed side members, said outside cleats of said first pair of opposed side members fitting into said slots formed by the cleats of said second pair of opposed side members, said inside cleats of said first pair of opposed side members being between the end cleats of said second pair of opposed side members, and said opposed end members being on the inside of the inside end cleats of said opposed side members.

6. A cleated box comprising, a first pair of opposed side members each including a substantially rectangular panel, an end cleat secured at each end edge of the panel on the inside thereof and an end cleat secured to said panel contiguous to but spaced from each end edge of the panel on the outside thereof and terminating short of the sides of the panel, a second pair of opposed side members each including a substantially rectangular panel with a cleat along each side edge on the inside thereof and a cleat along each end edge on the inside thereof which bridges the ends of the side cleats thereof, and a pair of opposed end members each including a panel, the cleats along the side edges of the second pair of opposed side members being located outside of the panels of the first pair of opposed side members, the ends of said outside cleats of said first pair of opposed side members bridging the side cleats of said second pair of opposed side members, said inside cleats of said first pair of opposed side

members being between the end cleats of said second pair of opposed side members, and said opposed end members being on the inside of the inside end cleats of said opposed side members.

7. A box including a first pair of spaced, opposed substantially rectangular side panels, a second pair of spaced, opposed substantially rectangular side panels extending transversely of and bridging said first pair of opposed panels, a first pair of cleats on the outside of each of said first pair of panels adjacent a first pair of opposite edges thereof, and a second pair of cleats on the outside of each of said first pair of panels bridging the opposite ends of said first pair of cleats thereon, and at least two of the cleats associated with each of said first pair of panels being slotted to permit free circulation of air when the cleated sides of similar boxes are placed in contact with each other. 15

8. A box including a first pair of spaced substantially rectangular horizontal panels constituting top and bottom walls of the box, and a pair of substantially rec- 20

tangular vertical side panels bridging the opposite sides of said spaced horizontal panels, a first pair of cleats located adjacent and extending most of the length of a first pair of opposed edges on the outside of at least 5 the uppermost of said horizontal panels, a second pair of cleats on the outside of said uppermost panel respectively bridging opposite ends of said first pair of cleats, said first and second pairs of cleats thereby enclosing the space ringed thereby, and at least one of said cleats having a slot formed in the bottom face thereof through which rain water falling into said space can drain.
